[57] **CLAIM**

I claim the ornamental design for a combined automobile body panels and roof rack, as shown and described.

DESCRIPTION

FIG. 1 is a perspective view of a combined automobile body panels and roof rack showing my new design;

FIG. 2 is a left side view;

FIG. 3 is a top view;

FIG. 4 is a front view; and,

FIG. 5 is a rear view.

The broken lines shown in all drawing views are for illustrative purposes only and form no part of the claimed design.
